AUTOMATIC FLUID-PRESSURE CUT-OFF.

1,155,915.

Specification of Letters Patent.

Patented Oct. 5, 1915.

Application filed September 9, 1914. Serial No. 860,882.

To all whom it may concern:

Be it known that I, MARTIN L. GROVE, a citizen of the United States, residing at Tylersburg, in the county of Clarion and 5 State of Pennsylvania, have invented a new and useful Automatic Fluid-Pressure Cut-Off, of which the following is a specification.

The invention relates to improvements in automatic fluid pressure cut offs.

10 The object of the present invention is to improve the construction of automatic cut offs shown and described in Patent No. 1,050,646, granted to me January 14, 1913, and to provide a simple, practical, and efficient automatic cut off of strong, durable, and comparatively inexpensive construction, 15 designed for use in various fluid pressure conduits, such as gas, water, steam, etc.; and operable through an abnormal increase in 20 the flow of such fluid pressure for positively cutting off the same without being affected by an abnormal decrease in the flow of the gas or other fluid pressure.

With these and other objects in view the 25 invention consists in the construction and novel combination of parts hereinafter fully described, illustrated in the accompanying drawing, and pointed out in the claims here- 30 to appended, it being understood that various changes in the form, proportion, size and minor details within the scope of the claims, may be resorted to without departing from the spirit or sacrificing any of the advantages of the invention.

35 In the drawing:—Figure 1 is a vertical longitudinal sectional view of an automatic cut off constructed in accordance with this invention, the parts being set for operation. Fig. 2 is a similar view, illustrating the 40 arrangement of the parts when tripped by an abnormal increase in the flow of the fluid pressure. Fig. 3 is a plan view, the top plate or cover being removed and the adjusting screw and the resetting screw being 45 sectioned.

Like numerals of reference designate corresponding parts in all the figures of the drawing.

In the accompanying drawing, in which 50 is illustrated the preferred embodiment of the invention, 1 designates an oblong casing designed to be constructed of cast metal or other suitable material and composed of integral bottom, side, and end walls, and a

removable top plate 2, which is secured by 55 bolts 3 or other suitable fastening devices to the body of the casing, a suitable packing 4 being interposed between the top plate or cover 2 and the body to provide a tight joint or connection.

The casing is divided by an integral transversely disposed vertical partition 5 into a front inlet compartment 6 and a rear outlet compartment 7, into which the fluid pressure passes from the inlet compartment 6 through a tubular connecting passage 8, formed integral with the partition and preferably located at the bottom thereof, as shown. The casing is provided at the front and rear end walls with threaded inlet and outlet openings 9 and 10, preferably in the form of nipples, as shown, and receiving the threaded ends 11 and 12 of inlet and outlet pipes 13 and 14, but the connection between the casing and the pipes may be made in any other 70 desired manner. The casing is equipped at the rear outlet compartment 7 with an outlet passage 15 of approximately L-shape, 75 consisting of a front vertical portion and a rearwardly extending horizontal portion, 80 which is connected with the outlet opening 10. The outlet passage 15 is preferably formed by integral walls or partitions, similar to the outlet of the casing of the aforesaid patent. The outlet passage, which extends upwardly from the bottom of the casing, terminates midway between the top and bottom thereof, being provided at the top with a valve seat 16 surrounding an 85 opening 17 and adapted to receive an automatically closing valve or closure 18, preferably in the form of a valve plug, as shown in the aforesaid patent, and carried by an oscillatory arm 19. The oscillatory arm 19 consists of a bar or piece pivotally mounted 90 at an intermediate point on a transverse pivot 20 and having a rear extension 21 adapted to be engaged by a resetting device 22. The valve or closure 18 is preferably 95 tapered to fit the opening 17, which is correspondingly tapered, and the said valve or closure is preferably provided with a gasket 23 consisting of a ring of rubber or any other suitable material, having its inner edge secured in an annular groove 24 in the valve 105 or closure, but any other suitable valve or closure may, of course, be employed. The pivot 20 is located above and slightly in

rear of the valve seat, and the oscillatory arm, which carries the valve or closure, extends upwardly and forwardly from the pivot, being arranged at an inclination when set for automatic operation. The valve or closure is preferably integral with the arm and the latter may also be thickened, as shown, adjacent to the valve plug or closure to secure the necessary weight and the desired pressure on the valve or closure when the same is in its closed position, as illustrated in Fig. 2 of the drawing.

The valve or closure, which, when released, automatically closes by gravity, is held in an open position by a latch 25, consisting of a bell crank lever fulcrumed at its angle on a transverse pivot pin 26 and composed of an upper rearwardly extending arm 27 and a front depending arm 28. The pivot 26 is located at the upper portion of the outlet compartment adjacent to the transverse partition 5, and the arm 27, which is arranged at an inclination, engages the oscillatory arm 19, which is provided adjacent to its front or upper end 29 with a flange or lug 30, forming a seat for the arm 27. The upper or front end 29 projects beyond the flange 30 and forms a shoulder for engaging with the arm 27 of the latch. The depending arm 28, which is in an approximately vertical position when the parts are set for automatic operation, as shown in Fig. 1, extends downwardly from the pivot to the connecting passage 8 and bears against the rear end of the tubular portion of the transverse partition and limits the downward movement of the upper arm. The depending arm is equipped at its lower end with a finger 31, extending into the passage 8 and also into the path of a closure 32, preferably in the form of a plug, as illustrated in the aforesaid patent, and carried by a bell crank lever 33, consisting of a relatively long depending arm 34 and a relatively short upper rearwardly extending arm 35. The bell crank lever 33, which is located within the inlet compartment, is fulcrumed at its angle on a transverse pivot pin 36, located above the connecting passage 8. The depending arm extends downwardly from the pivot 36 to the front end of the connecting passage 8, and the closure is provided with a tapered portion 37 to fit the front portion 38 of the connecting passage, which is correspondingly tapered, and the said closure 32 is also provided with an integral stop flange 39 for limiting the inward or rearward movement of the closure to prevent the same from becoming wedged or sticking in the tapered front portion 38 of the said passage. Any other suitable form of closure may, of course, be employed, and when the said closure 32 moves inwardly or rearwardly to its closed position shown in Fig. 2, it engages the finger 31 and forces

the same rearwardly to lift the upper arm 27 of the latch out of engagement with the oscillatory arm 19 to permit the valve or closure 18 to be swung by gravity to its closed position.

A coiled spring 40, which bears upon the front arm 35 and yieldably maintains the closure 32 in the open position shown in Fig. 1, is engaged by one arm of a lever 41, pivoted at an intermediate point on a transverse pivot 42 and having its other end 43 forked or bifurcated to engage an annular groove 44 of an adjusting screw 45, mounted in a threaded opening in the top plate or cover of the casing and adapted to be adjusted to vary the tension of the spring 40 and thereby adjust the automatic cut off to close under the desired increase in the flow of the fluid pressure through the connecting passage. The tension adjusting means is substantially the same as that shown and described in the aforesaid patent, with the exception that the upper end 46 of the adjusting screw is squared for the reception of a key, instead of being provided with an end slot. Any other preferred form of adjusting means may, of course, be employed.

The casing is equipped at the front with a screen 47 similar to that shown in the aforesaid patent, and the resetting device 32, which is adapted to swing the oscillatory arm 19 upwardly to reengage the same with the latch, preferably consists of a screw mounted in a threaded opening at the top or cover of the casing and adapted to be screwed downwardly from the position shown in Fig. 2 to that illustrated in Fig. 1. When the oscillatory arm is swung downwardly to close the outlet and cut off the flow of the fluid through the device, the rearward extension 21 is arranged in a substantially horizontal position and the downward movement of the resetting screw 22 carries a lower rounded head 48 thereof into engagement with the extension 21 and lifts the valve or closure 18. The arm 19, in its upward movement, contacts with the arm 27 of the latch, lifting the said arm 27, which drops into engagement with the end 29 of the said arm 19 and rests upon the seat 30 as soon as the said end 29 is carried beyond the rear end of the arm 27 of the latch by the resetting device. The resetting device is then moved upwardly from the position shown in Fig. 1 to that illustrated in Fig. 2, and the parts of the automatic cut off are then in position for operation by a predetermined increase in the flow of the fluid pressure.

The gas or other fluid pressure enters the casing at the inlet 9 and the impurities are screened out by the screen 47. If the flow of the gas is normal or below normal, the closure 32 will remain open and any gas entering the casing will pass through the

intermediate passage 8 from the front or inlet compartment, into the rear or outlet compartment, and pass out of the casing through the passage 15. Any decrease or cessation of the flow of the fluid pressure will not operate to trip the automatically closable valve or closure 24, but should the flow, through any cause, increase beyond a predetermined point, it will overcome the pressure of the spring 40 and carry the tripping device formed by the closure 32 and the oscillatory arm 34 into engagement with the finger of the latch lever and lift the arm 27 of the latter. This will permit the valve or closure to close and seat itself and cut off the flow of fluid pressure through the outlet passage 15. After an automatic operation of the cut off, the valve or closure 18 will remain in its closed position until reset by the resetting device 22.

What is claimed is:

1. An automatic fluid pressure cut off including a casing having an inlet and an outlet and provided with a passage, an automatically closable valve or closure for cutting off the flow of fluid pressure through the outlet, a latch for normally holding the valve or closure in its open position, and a closure for the said passage yieldably maintained in an open position and operable through an abnormal increase in the flow and movable into engagement with the latch to release the said valve or closure.

2. An automatic fluid pressure cut off including a casing having inlet and outlet compartments and a connecting passage, an automatically closable valve for cutting off the flow of fluid pressure, a latch arranged to hold the valve or closure in an open position and having a finger or portion extending into the said passage, and a tripping

device operable through the abnormal increase in the fluid pressure through the passage and arranged to engage the said finger or portion to trip the valve or closure. 45

3. An automatic fluid pressure cut off including a casing having inlet and outlet compartments and a connecting passage, an automatically closable valve for cutting off the flow of fluid pressure, a latch consisting of a bell crank lever having one arm arranged to engage and hold the valve or closure in the open position thereof, the other arm of the bell crank lever being provided with a finger extending into the passage, and a closure located in the inlet compartment and yieldably maintained in an open position and closable through an abnormal increase in the fluid pressure, the last mentioned closure being movable into and out of engagement with the finger and adapted to trip the said valve or closure. 55

4. An automatic fluid pressure cut off comprising a casing having inlet and outlet compartments and a connecting passage, 65 said casing being also provided with an outlet, an automatically closable valve or closure for cutting off the flow through the outlet, a latch device for holding the said valve or closure in its open position, and a tripping device including a closure adapted to close the intermediate passage, said latch device being arranged to be engaged and operated by the last mentioned closure to release the said valve or closure. 70

In testimony, that I claim the foregoing as my own, I have hereto affixed my signature in the presence of two witnesses.
